DESIGN FOR A SANDAL

William H. Joyce, Jr., Pasadena, Calif.

Application May 9, 1935, Serial No. 56,749

Term of patent 3½ years

To all whom it may concern:

Be it known that I, William H. Joyce, Jr., a citizen of the United States and resident of Pasadena, in the county of Los Angeles and State of California, have invented a new, original, and ornamental Design for a Sandal, of which the following is a specification, reference being had to the accompanying drawing, forming part thereof, in which,

Fig. 1 is a plan view of the sandal showing my new design; and

Fig. 2 is a side perspective view of the sandal shown in Fig. 1.

A dominant feature of the design resides in the formation of the vamp with the two side pieces, each extending for a substantial distance along the sole of the shoe and having a plurality of upwardly extending tongues attached to a central T-strap.

I claim:

The ornamental design for a sandal as shown and described.
